UNITED STATES PATENT OFFICE.

APCAR YOSGATT, OF HOBOKEN, NEW JERSEY.

SOLE CLAMP.

Application filed January 7, 1927. Serial No. 159,562.

This invention is particularly intended to facilitate the repair of shoes when outsoles are to be cemented to shoe bottoms, either as the only means of fastening or preliminary 5 to subsequent stitching. It is also applicable when soles are to be applied to new shoes in the process of manufacture.

One object is to provide a clamp which will apply pressure over substantially the entire 10 area of the sole and especially along the edge, and which will be applicable to a considerable range of lengths, widths and contours of shoes. Further objects are to provide a clamp, one plate of which bears against the 15 inner side of the shoe bottom and which is readily applied and removed.

In the accompanying two sheets of drawings which form a part of this description,

Figure 1 shows a clamp which embodies 20 this invention together with a shoe to which it is applied, in section on the lines I—I of Figs. 2, 4, and 5.

Fig. 2 shows the clamp and shoe in section on the lines II—II of Figs. 1, 4, and 5.

Fig. 3 shows the foot of the clamp and pressure plates which bear against the inner side 25 of the shoe bottom.

Fig. 4 shows the shoe from the upper side with the shoe clamp applied.

Fig. 5 shows the shoe from the under side 30 with the shoe clamp applied.

The clamp comprises a connecting member with an upper part 10 and a lower part 11, the two parts being hinged together at a hinge 35 joint 12 midway of the clamp to facilitate setting in place and removal. A cap plate 13 bridges the hinge joint and is secured by screws 14, 15 to both parts of the connecting member for clamping the joint.

The upper part of the connecting member 40 is bent twice at right angles so that its end can enter the shoe, and its end has lateral forks 16, 16 to which a foot plate 17 is attached. This plate has four groups of inter- 45 communicating slots 18, 18, and pressure plates 19, 19 underlie each and are adjustably secured to the foot plate by bolts 20, 20 which pass through the slots. The pressure plates are spread so as to cover the inner side of the 50 shoe bottom as fully as possible.

The under portion of the connecting member is bent at right angles and its end has lateral forks 21, 21 through the ends of which clamp screws 22, 22 are threaded. The clamp 55 screws are set against an outsole bearing plate 23 the margin of which is within the margin

of the outsole so that it only bears against the middle portion of the outsole. The contour shown is suitable for a left shoe and will be the reverse for a right shoe. In the face of 60 this bearing plate and adjoining its curved margin is a T-slot 24.

As the inside pressure plates cannot fully cover the shoe bottom, particularly in the case of a shoe of the welt type the bearing 65 plate which bears against the outsole is not made to wholly cover the outsole, and additional marginal clamps are provided. Each of these comprises an upper jaw 25 and a lower jaw 26. A fork 27 hinged to the lower 70 jaw carries a clamping screw 28, the end of which slides on a cam surface formed on the top of the upper jaw when the fork is folded to or from the clamping position. The lower jaw has a slotted tail 29 which crosses 75 the T-slot in the outsole bearing plate, and is held thereto by a bolt 30 which passes through the slotted tail and has its head engaged by the T-slot. A wing-nut 31 is used on the bolt. By reason of the two slots crossing each other, the position of the margin clamp is adjustable longitudinally, transversely and angularly in position so that it can be brought into position for proper engagement with the welt and the margin of the 80 outsole.

In using the clamp, cement is first applied to the shoe bottom and to the outsole and the outsole is laid on the shoe bottom. The shoe clamp is then set in place, the hinge joint is 90 clamped, and the clamping screws are set up to press the outsole bearing plate against the middle of the outsole. The margin clamps are adjusted in position and secured to the outsole against the middle of the outsole. 95 The margin clamps are adjusted in position and secured to the outsole bearing plate and are then closed by the ends of the clamping screws riding on the cam surfaces of the upper jaws. If clamping by this means is insufficient the clamping screws are set up. The clamp is allowed to remain on the shoe for from twenty to thirty minutes usually so as to give the cement the proper time to set.

I claim,

1. A sole clamp for pressing an outsole against a shoe bottom provided with a foot, and a plurality of pressure plates which are adjustably secured to the foot for bearing directly against the inner side of the shoe 110 bottom.

2. A sole clamp for pressing an outsole

- against a shoe bottom by engagement with the inner side of the shoe bottom and the outer side of the outsole in which the connecting member of the clamp is provided midway 5 with a hinge joint, means for clamping the joint, and independent means for operating the clamp.
3. A sole clamp for pressing an outsole against a shoe bottom having plates for bearing against the inner side of the shoe bottom and the middle portion of the outsole, and means for pressing the plates towards each other in combination with marginal clamps adjustably connected to the plate which bears 10 against the middle portion of the outsole.
4. A sole clamp for pressing an outsole against a shoe bottom having plates for bearing against the inner side of the shoe bottom and the middle portion of the outsole, and means for pressing the plates towards each other in combination with marginal clamps 20 adjustably connected to the plate which bears against the middle portion of the outsole, the connecting means for the marginal clamps consisting of a T-slot in the outsole bearing plate and slotted tails attached to the clamps with clamping bolts which pass through the tails and have their heads engaged by the T-slot. 25

APCAR YOSGATT.
